ELECTRODE FEEDING MECHANISM FOR
ARC SEARCHLIGHTS

Carl F. Herbold, Lakewood, Ohio, assignor to
Westinghouse Electric & Manufacturing Com-
pany, East Pittsburgh, Pa., a corporation of
Pennsylvania

Application July 17, 1937, Serial No. 154,253

9 Claims. (Cl. 176—71)

My invention relates, generally, to arc searchlights and, particularly, to improvements in electrode feeding mechanisms for arc searchlights.

In the operation of arc searchlights, it is necessary that the arcing tip of the positive electrode be maintained at, or very near to, the focal point of the reflector of the searchlight so that the most efficient beam may be produced.

Because the positive electrode burns away very rapidly, it is necessary that some means be provided for feeding the positive electrode to the arc to compensate for the consumption of the electrode in the arc.

It is common practice to cause the positive electrode to move toward the arc in response to electromagnetic devices which are controlled by thermostatic circuit controllers actuated by the heat from the electrode tip and so positioned as to be actuated when the electrode tip has receded a predetermined amount from the desired position. Such a device is shown in the patent to A. P. Davis, 1,433,073, October 24, 1922.

The object of my invention is to provide a feeding mechanism for the positive electrode of an arc searchlight which shall function to feed the electrode at a constant rate which may be adjusted to compensate for consumption of the electrode in the arc.

Another object of the invention is to provide a feeding mechanism for an electrode of an arc searchlight which may be caused to feed the electrode either automatically in response to the positioning of the arcing tip of the electrode, or continuously at a predetermined constant rate.

Another object of the invention is to provide an improved electrically controlled system for feeding an electrode of an arc searchlight.

These and other objects of the invention will be apparent from the following detailed description taken in connection with the accompanying drawing of which.

Figure 1 is a diagrammatic illustration of an electrode feeding mechanism for arc searchlights as embodied in the teachings of the invention.

Fig. 2 is an enlarged sectional view of the gear mechanism of Fig. 1.

Fig. 3 is an enlarged longitudinal sectional view of the control drum of Fig. 1 with the adjustable brush in contact with the contact strip on the drum, and

Fig. 4 is an enlarged sectional view of the control drum of Fig. 1 with the drum rotated 90° from the position of the section of Fig. 3.

In carrying out my invention, I provide a mechanism for continuously rotating the positive elec-

trode of an arc searchlight having an electromagnetically operated device for causing the mechanism to feed the electrode with a circuit for energizing the electromagnetically operated device intermittently at a substantially constant rate. Means are provided for varying the length of the periods of energization of the electromagnetically operated device at will.

A thermostatically controlled circuit is also provided for energizing the electromagnetically operated device in response to the positioning of the arcing tip of the electrode. Means are provided for selectively placing the electromagnetically operated feeding control under the control of the thermostatically operated circuit or the constant feed circuit.

Referring to the drawing, the positive and negative electrodes 2 and 3 are energized from the source of current XY through conductors 4 and 5, respectively. The positive electrode is constantly rotated by a mechanism similar to that disclosed in the copending application of William H. Jacobs et al., Serial No. 43,372, filed October 3, 1935, now Patent No. 2,177,888, having a common assignee with this application. This rotating mechanism comprises rollers 6 and 7 which are made to bear upon the electrode by tension of the spring 8 and which are hinged on the head piece 9.

The head piece 9 is rotated through connection with gear 10 which is driven by a motor 11 through shaft 12 and pinion 13. By this mechanism, the positive electrode is continuously rotated while the motor 11 is energized.

The movement of the positive electrode toward the negative electrode to compensate for consumption of the positive electrode in the arc is accomplished by a mechanism which comprises a worm 14 which acts upon a worm wheel mechanically connected with roller 7 to provide rotation of roller 7 which, in turn, causes a movement of the positive electrode. The worm 14 is connected with gear 16 through shaft 15 and is driven by gear 17 when there is relative motion between the gear 17 and the head 9. A ring 18 having a series of protuberances 39 on its periphery is secured to gear 17 and both gears 17 and ring 18 are mounted for rotation upon the sleeve 19 which connects the head 9 with the bevel gear 10.

In the normal operation of the mechanism to rotate the electrode 2 there is no relative rotation between the gear 17 and the head 9, since the gear 17 is made to rotate with the head 9, the gear 17 being carried around by its contact with gear 16. It will be seen that while the head

9 is rotated, if the rotation of the gear 17 is stopped, gear 16 will roll upon the periphery of gear 17 and this will cause rotation of worm 14 which, in turn, will cause roller 7 to rotate to 5 produce a feeding movement of the electrode 2.

The stopping of the gear 17 to cause feeding movement of the electrode 2 is effected by the movement of detent 20 to form a stop for one of the protuberances 39 of ring 18. The movement 10 of detent 20 to its position in engagement with the ring 18 is produced by a solenoid 21. Thus, it will be seen that the electrode 2 is continuously rotating and is moved toward the negative electrode only while the solenoid 21 is energized.

15 The energization of the solenoid 21 is governed by the controller 22 in cooperation with the thermostat 23. The controller 22 comprises a drum 10 of insulating material 24 which is continuously driven by a motor 11 through shaft 36 and cooperating gears 37 and 38. On the surface of the drum there is disposed a metallic contact ring 25 of uniform width and a metallic contact ring 26 which has a substantially triangular segment 27 extending therefrom along the drum surface. 20 A fixed brush member 28 is positioned to continuously engage ring 26 and a second fixed brush member 29 is positioned to continuously engage the ring 25. A third brush member 30 is so mounted as to be movable axially of, and to 25 remain in contact with, the drum surface.

The thermostat may be of any suitable type so positioned as to close its contact members when the arc tip of the electrode 2 has receded from its desired position a predetermined amount, and 30 may be such an arrangement as shown in the co-pending application of P. H. Brace et al., Serial No. 130,740, filed March 13, 1937, now Patent No. 2,162,524 issued June 13, 1939. When brush 30 is so positioned as to continuously engage ring 25, the detent solenoid 21 will be energized to cause feeding of the electrode 2 toward the positive electrode when the thermostat 23 is closed through a circuit which extends from conductor X through conductor 31, relay 21, conductor 32, brush 30, ring 25, brush 29, conductor 33, contact members of thermostat 23 and conductor 34 to the conductor Y.

When the movable brush 30 is so positioned as to engage the conducting segment 27 as it is rotated with the drum, the positive electrode 2 will be fed toward the negative electrode by energization of solenoid 21 through a circuit which extends from conductor X, through conductor 31, solenoid 21, conductor 32, brush 30, segment 27, brush 28 and conductor 35 to conductor Y.

In the operation of the device, when it is desired to control the feeding of the positive electrode to the arc in response to a predetermined movement of the electrode tip from its desired 60 position, brush 30 is moved to a position to continuously engage ring 25 as the drum rotates, and solenoid 21 acts to cause movement of the positive electrode so long as the electrode tip remains in such a position as to cause the thermostat 23 to hold its contact members closed. When the arcing tip of positive electrode 2 has been advanced to where the heat from the electrode tip no longer affects the thermostat 23, the feeding of the electrode is stopped by deenergization of 65 the circuit through solenoid 21 by opening of the contact members of the thermostat.

In the event of failure of the thermostat 23 to function properly or in the event that it should be found desirable to feed the positive electrode toward the negative electrode at a pre- 70

determined constant rate, the brush 30 may be moved to such a position as to engage the segment 27 on each revolution of the drum 24. This engagement of brush 30 and segment 27 will cause energization of solenoid 21 through the circuit hereinbefore described for a length of time depending upon the length of time that brush 30 engages segment 27.

By moving the brush 30 axially along the surface of the drum 24, it may be made to remain in contact with segment 27 varying lengths of time on each revolution of the drum 24. The brush may be so positioned as to make the periods of energization of the solenoid 21 such as to cause the feeding of the positive electrode 2 at a rate 15 which will just compensate for the rate of consumption of the electrode in the arc and which will thus maintain the arcing tip of the electrode 22 substantially continuously in its desired position. 20

It will be seen that I have provided a mechanism which is simple and reliable in operation and inexpensive of manufacture, which will function to maintain the arcing tip of the positive electrode of an arc searchlight in a predetermined 25 position either in response to a predetermined recession of the arcing tip due to consumption of the electrode in the arc or continuously at an adjustable rate corresponding to the rate of consumption of the electrode in the arc. 30

In compliance with the requirements of the patent statutes, I have shown and described herein a preferred embodiment of my invention. It is to be understood, however, that the invention is not limited to the precise construction shown 35 and described, but is capable of modification by one skilled in the art, the embodiments herein shown being merely illustrative of the principles of my invention.

I claim as my invention:

1. In an electrode feeding device having an electromagnetic actuating mechanism, means for intermittently energizing the actuating mechanism comprising a circuit and an interrupter for said circuit, said interrupter comprising a rotating non-conducting drum, a conducting strip mounted on said drum, said strip increasing in length from one end to the other and extending axially of said drum, brush means bearing on said drum and disposed to intermittently complete said circuit, said brush means being movable axially of the drum to vary the interval of contact engagement with said strip as the drum rotates. 40

2. In a feeding mechanism for an arc searchlight electrode, a controller comprising a rotatable drum having an electrically conducting band thereon, a substantially triangular shaped electrically conducting segment extending axially along said drum surface from said band, brush means engaging said band and a second brush means engaging said drum and adjustable axially along said drum surface so as to vary the duration of contact of said second brush with said triangular shaped segment as said drum rotates. 55

3. In a feeding mechanism for an arc searchlight electrode, a controller comprising a rotatable drum having an electrically conducting band thereon, a substantially triangular shaped electrically conducting segment extending axially 70 along said drum surface from said band, brush means engaging said band, a second brush means engaging said drum and movable axially along said drum surface so as to vary the duration of contact of said second brush with said triangular 75

shaped segment as said drum rotates, means for continuously rotating the electrode, electromagnetic means connected with said controller and cooperating with said rotating means for feeding said electrode, and means whereby said controller is rotated by said rotating means.

4. In a feeding mechanism for an arc search-light electrode, a controller comprising a rotatable drum having a pair of spaced electrically conducting bands thereon, a substantially triangular shaped electrically conducting segment extending axially along said drum surface from one of said bands, brush means engaging each of said bands, brush means engaging said drum and movable axially along said drum surface, to vary the duration of contact of said slidable brush with said triangular shaped segment as said drum rotates and to contact either of said bands.

5. In an electrode feeding mechanism for an arc searchlight, means for continuously rotating the electrode, electromagnetically operated means cooperating with said rotating means for feeding said electrode, and means for selectively energizing said electromagnetic means either in response to the positioning of the electrode tip or intermittently at a predetermined rate, said energizing means comprising a rotatable drum having a pair of spaced electrically conducting bands thereon, a substantially triangular shaped electrically conducting segment extending axially along said drum surface from one of said bands, brush means bearing on each of said bands, brush means bearing on said drum and slidable axially along said drum surface to vary the duration of contact of said slidable brush with said triangular segment as said drum rotates and to contact either of said bands, circuit means whereby said electromagnetic means is energized directly when said slidable brush is positioned to engage said triangular segment or its associated band and through a switching device which is responsive to the positioning of the electrode tip when the slidable brush is in contact with said second band, and means whereby said electrode rotating means also rotates said drum.

6. In an electrode feeding mechanism for an arc searchlight, means for continuously rotating the electrode, electromagnetically operated means cooperating with said rotating means for feeding the electrode, an energizing circuit for said electromagnetically operated means, including circuit interrupter means continuously driven by

said rotating means for intermittently closing said energizing circuit, auxiliary circuit control means for said energizing circuit, controlled by the positioning of the arcing tip of the electrode, and means including a portion of said circuit interrupter means for selectively rendering said circuit interrupter means and said auxiliary circuit control means effective to control said energizing circuit.

7. In an electrode feeding mechanism for an arc searchlight, means for continuously rotating the electrode, electromagnetically operated means cooperating with said rotating means for feeding the electrode, an energizing circuit for said electromagnetically operated means, including circuit interrupter means continuously driven by said rotating means for intermittently closing said energizing circuit, auxiliary circuit control means for said energizing circuit controlled by the positioning of the arcing tip of the electrode, and relatively adjustable means including a portion of said circuit interrupter means for selectively rendering said circuit interrupter means and said auxiliary circuit control means effective to control said energizing circuit and for varying the length of the periods of closure of said energizing circuit by said circuit interrupter means.

8. In an electrode control system for a lighting device having arcing electrodes, means for feeding an electrode, main control means for causing said feeding means to feed the electrode at a substantially constant rate, supplemental control means for causing said feeding means to feed the electrode in response to the positioning of the electrode arcing tip, and selectively operable auxiliary circuit control means for selecting for operation said main control means and said supplemental control means.

9. In an electrode control system for a lighting device having arcing electrodes, means for feeding an electrode, main control means for causing said feeding means to feed the electrode at a substantially constant rate, supplemental control means for causing said feeding means to feed the electrode in response to the positioning of the electrode arcing tip, and adjustable selectively operable auxiliary circuit control means for selecting for operation said main control means and said supplemental control means and for varying the rate of feed controlled by said main control means.

CARL F. HERBOLD.
